[57] CLAIM

The ornamental design for a figurine of a Dalmatian, substantially as shown and described.

DESCRIPTION

FIG. 1 is a front end elevational view of the figurine of a Dalmatian showing our new design;

FIG. 2 is a rear end perspective view of FIG. 1;

FIG. 3 is a side perspective view of FIG. 1;

FIG. 4 is an opposite side elevational view showing the side opposite that shown in FIG. 3; and
